US0D1046614S

(12) United States Design Patent (10) Patent No.: US D1,046,614 S
(45) Date of Patent: * Oct. 15, 2024

(54) ORAL CARE PACKAGE WITH SURFACE ORNAMENTATION

- (71) Applicant: The Procter & Gamble Company, Cincinnati, OH (US)
- (72) Inventors: Kartika Huston Redding, Cincinnati, OH (US); Xiaojie Geng, Beijing (CN); Ming Qi, Beijing (CN)
- (73) Assignee: The Procter & Gamble Company, Cincinnati, OH (US)
- () Term: 15 Years
- (21) Appl. No.: 29/800,403
- (22) Filed: Jul. 21, 2021

Related U.S. Application Data

- (62) Division of application No. 29/726,220, filed on Mar. 2, 2020, now Pat. No. Des. 928,607, which is a division of application No. 29/647,235, filed on May 10, 2018, now Pat. No. Des. 880,293.

(30) Foreign Application Priority Data

- Nov. 17, 2017 (CN) 201730569987.3
